VENTURI TYPE CYLINDER HEAD

Caleb E. Summers, Pontiac, Mich., assignor to
 General Motors Corporation, Detroit, Mich., a
 corporation of Delaware

Application February 20, 1933, Serial No. 657,624

6 Claims. (Cl. 123—191)

This invention relates to internal combustion engines and has particular reference to an improved combustion chamber in the cylinder head.

The objects of the invention are to provide means to direct the flow of gases through the exhaust valve in smooth flow lines; to reduce the temperature of the exhaust valve by providing a water cooled surface at a minimum distance from the valve when in open position; and break the flat surface of the combustion chamber and introduce cooled walls to reduce the temperature of the compressed charge and also to influence the direction of currents and the rate of burn of the combustible charge; to fill up the dead space in the combustion chamber with water cooled iron thereby giving more room along the normal flow paths of the gases; and by the combination of these advantages to enable the use of higher compression without detonation and therefore obtain greater power and economy with smooth engine operation.

To accomplish the objects of the invention the combustible chamber is formed by providing a boss or projection which extends from the water jacket of the cylinder head inwardly of the combustion chamber over the exhaust valve to give a flat water cooled surface closely adjacent the exhaust valve when in open position. The application of such a boss reduces the amount of combustible gas over the exhaust valve when in closed position and accordingly reduces the volume of gas heated. There is therefore obtained the double advantage of reducing the temperature of the exhaust valve and also reducing the volume of gases subjected to its temperature. The boss or projection is so shaped that when the exhaust valve is in fully opened position the valve and boss will form continuations of each other to give smooth flow lines for the exhaust gases.

By the provision of the boss or projection in the combustion chamber over the exhaust valve the volume of the chamber is reduced which will allow a corresponding increase in volume over the inlet valve where it is desired and will allow an easier inflow of fuel mixture. The volume of the combustion chamber due to the provision of the boss can be so proportioned that an increased compression ratio is obtained without changing the other structure or characteristics of the engine.

The invention is disclosed on the accompanying drawing in which:

Figure 1 is a sectional view through one cylinder and the head of a multi-cylinder internal

combustion engine, the section being taken through the exhaust valve.

Figure 2 is a bottom plan view of the cylinder head showing combustion chambers and taken on the line 2—2 of Figure 1.

Figures 3 and 4 are sections taken on the lines 3—3 and 4—4 of Figure 2.

Figure 5 is a vertical sectional view parallel to the valve stems through the top of one cylinder showing a modified form of my invention.

On the drawing, the numeral 2 indicates an internal combustion engine as a whole. The engine has a plurality of cylinders, one of which is indicated at 4 and in each of which there operates a piston 6 connected in the usual manner to a connecting rod by the wrist pin 8. The engine has the usual water jacket 10 for the cooling system of the engine. Suitable sleeves 12 mounted in the engine block receive the stems 14 of the exhaust valves 16, the heads of which are indicated at 18. The cylinder block is formed with the usual valve seats 20 to cooperate with the seats 22 on the valve heads 18.

The cylinder head is indicated at 24 and is connected to the main cylinder block by means of bolts 26 and nuts 28, a gasket 30 being interposed between the head and the block. The water circulating system 18 is connected by means of a plurality of passages 32 and 34 with the water jacket 36 of the cylinder head 24.

The parts so far described are conventional and per se form no part of the invention.

The novel combustion chamber of the invention is indicated as a whole at 38. The upper wall 40 of the combustion chamber likewise forms one wall of the water jacket 36 and a boss or projection 42 extends downwardly from the water jacket and inwardly of the combustion chamber and over the head 18 of the exhaust valve 16. The bottom of the boss 42 is substantially flat 40 and is in very close proximity of the head 18 of the exhaust valve when the latter is in open position as shown in Figure 1. This position leaves but a very thin or small space 44 between the valve head 18 and the projection 42 and correspondingly reduces the volume of the combustion chamber 38. The combustion chamber ordinarily continues in a substantially straight line as is indicated by the dotted line 46 which shows the top of a combustion chamber over the inlet valve. It is therefore apparent that the volume over the exhaust valve in open position has been greatly reduced which correspondingly reduces the volume of the hot exhaust gases thereover when the valve is in the closed position. The 55

spark plug openings 47 are positioned close to the boss 42 so the spark plug points will be close to the small volume of relatively hot gases over the valve.

- 5 By referring to Figure 1 it will be noted that the wall 48 of the combustion chamber immediately above the boss 42, the side of the valve at the valve seat 22, and the conical continuation 49 of the valve head form smooth flow lines which 10 will aid the exhaust gases in passing from the combustion chamber 38. If the boss 42 were not present there would be the large space between the dotted line 46 and the top of the head 18 which would disturb the smooth flow of gases 15 through the exhaust valve opening and leave a much larger amount of exhaust gas to heat the valve. The presence of the boss and the provision of the smooth lines at the sides of the boss and on the valve greatly aid the exhaust gases 20 in leaving the combustion chamber. The exhaust gases are deflected by the boss 42 so that a smooth flow curve is established as the gases leave the valve opening. This reduces back pressure and permits a more thorough scavenging of the combustion chamber and prevents the fire from impinging directly on the valve. During the period when the exhaust valve is near wide open position the proximity of its heated head 18 to the relatively cool boss 42 reduces the temperature 30 of the valve. Even when the valve head 18 is on its seat the distance from the top of the head to the water cooled surface of the boss 42 is only approximately half as great as in the conventional combustion chamber.
- 35 The temperature of the gases in the combustion chamber 38 just before ignition varies with their proximity to heated surfaces. The importance of this temperature is again dependent on the volume of gases so heated. The volume of gas 40 above the exhaust valve head 18 is reduced to approximately half the normal volume, therefore its importance as an area of rapid flame travel is accordingly diminished. There is therefore the double advantage of reducing the temperature of 45 the exhaust valve and also reducing the volume of gases subjected to its temperature.

In a high compression motor, particularly of short stroke, the volume of the combustion chamber becomes small and where through necessity 50 its area must be considerably extended to provide ample space for valves, etc., the combustion chamber becomes too thin to afford ample passage for the gases from the inlet valve and to the exhaust valve. In the structure described 55 above the practically dead space above the exhaust valve which has little value as a passage for gases is filled with metal. In addition to having the cooling and air flow advantages previously mentioned, there is a reduction in the 60 total volume of the combustion chamber so additional volume can be applied at points where it is required. Thus, by filling the dead space above the exhaust valve it is possible to lift the space above the inlet valve, giving room for the 65 incoming gases to flow around and over the inlet valve with minimum obstruction.

The location of a boss projecting from the water cooled metal of the cylinder head in a place where it is in itself beneficial has the 70 further advantage of changing the shape of the combustion chamber and breaking up the long straight lines which bring about too rapid flame propagation. The location for the spark plug is also chosen so it is near the small volume of 75 relatively hot gas over the exhaust valve so this

can be fired as a primer for the entire charge at the beginning of combustion while the rate of flame propagation is low.

In Figure 5 is illustrated a modification of my invention in which a projection is provided over both the inlet and exhaust valves. The exhaust valve head 18 has the projection 42 extending down toward it from the motor head 24 as before. An inlet valve head 50 is located adjacent the exhaust valve and has a projection 42' extending down toward the valve from the head 24' in exactly the same manner. Such a cylinder head having the two bosses in each combustion chamber has been built and used, but in the particular design of the motor desired to be used at the time, this second boss over the inlet valve was found not to be necessary. The second boss, however, is fundamentally an essential part of the structure of the invention which is to provide a streamline passage for the flow of gas to and from the combustion chamber.

In ordinary practice where the conventional type of combustion chamber is used having an appreciable space between the tops of the valves in open position and the top of the combustion chamber the flow out from or into the combustion chamber entails an abrupt change in direction of the flow and the sacrifice of practically all the energy represented by the inertia of the gases. The application of this streamlining structure to the combustion chamber over the inlet valve is more important insofar as increasing the volumetric efficiency of the motor is concerned than is the streamlining of the exhaust valve.

A practical need for a structure which involves the use of bosses over both the inlet and exhaust valves is appearing in the present state of the internal combustion engine art. Experiments conducted along the lines of disclosure of the invention have disclosed that it is difficult with L 40 head engines to reduce the volume of the combustion chamber to obtain the high compression ratio needed for ethyl gasoline when the valves are amply spaced to facilitate cooling of the engine block. By eliminating the waste space over 45 the tops of the valves it increases available space for the flow of gas to and from the valve.

In applying a boss 42 over the inlet valve the boss is constructed similarly to the boss 42 over the exhaust valve, or if desired, the two bosses 50 may unite at their adjacent sides to form one integral or elongated boss.

I claim:

1. In an internal combustion engine having inlet and exhaust valves and a combustion chamber, said engine having a jacketed cooling system, a non-recessed solid boss extending from the cooling system into the combustion chamber over the exhaust valve, said boss having a substantially round flat surface in close proximity to the valve 60 when the latter is in open position.

2. In an internal combustion engine having inlet and exhaust valves and a combustion chamber, said engine having a jacketed cooling system, a boss extending from the cooling system into the combustion chamber over the exhaust valve, said boss being in close proximity to the valve 65 when the latter is in open position, the side of said valve in its open position forming substantially a continuation of the side of the boss to 70 form a smooth surface for the outflow of gases.

3. In an internal combustion engine having a cooling system, inlet and exhaust valves, and a combustion chamber, a boss or projection extending from the cooling system into the combustion 75

chamber to form a cooling surface closely adjacent the exhaust valve, said exhaust valve in open position, extending very close to the projection, the sides of said exhaust valve in its open position forming a substantial continuation of the sides of the projection to give a smooth flow or stream line construction within the combustion chamber to facilitate the outflow of exhaust gases, and a smooth surface free of projections over the remainder of the extent of the combustion chamber.

4. In an internal combustion engine having a cooling system, inlet and outlet valves, and a combustion chamber, a solid boss projecting from the cooling system into the combustion chamber and positioned in a place not actively used for the transfer of gases, said boss facilitating the outflow of exhaust gases from the chamber and reducing the combustion chamber space.

5. In an internal combustion engine having a cooling system, inlet and outlet valves, and a combustion chamber, a boss projecting from the

cooling system into the combustion chamber and positioned in very close proximity to the outlet valve when said valve is in open position, said exhaust valve in open position forming a substantial continuation of said boss to form a substantially smooth stream line part for the flow of exhaust gases, the remainder of said combustion chamber being substantially smooth and free from obstructions, said boss decreasing the volume of the combustion chamber to cause an increase in the compression ratio.

6. In an internal combustion engine having inlet and exhaust valves and a combustion chamber, said engine having a jacketed cooling system, a solid boss extending from the cooling system into the combustion chamber over the exhaust valve, a separate second solid boss extending from the cooling system into the combustion chamber over the inlet valve, said bosses being in close proximity to the valves when the latter are in open position.
